AMUSEMENT DEVICE

Filed June 1, 1927

UNITED STATES PATENT OFFICE.

HAROLD T. PULSIFER, OF NEW YORK, N. Y.

AMUSEMENT DEVICE.

Application filed June 1, 1927. Serial No. 195,770.

My invention consists in the novel features hereinafter described, reference being had to the accompanying drawing which shows several embodiments of the invention selected 5 by me for purposes of illustration, and the said invention is fully disclosed in the following description and claims.

The essential feature of the invention is the propulsion of passenger carrying, floating, 10 rolling or sliding vehicles upon a suitable supporting surface by means of an artificially created draft of air operating upon sails carried by the vehicles, the vehicles being each capable of uncircumscribed and independent 15 movement under the direction of an operator carried by the vehicle, who controls the direction of movement by means of the sails and the usual steering means with which the vehicles are ordinarily provided, for the purpose 20 of amusement and recreation. The supporting surface may be water, ice, or a smooth floor or pavement, and by the term vehicle I include sail boats, sail vehicles on wheels or rollers, ice boats or skates provided with runners or rollers. In the case of boats, vehicles 25 on wheels or runners, and ice boats, the sails may be either of the square or fore-and-aft variety, and such boats or vehicles will be provided with the usual steering means controlled 30 by an operator carried on the vehicle. In the case of skaters, the sails will ordinarily be similar to those usually employed in skating with the aid of the wind in the open, and the skates will be steered by the skater in the 35 usual manner. In any embodiment of the invention the propelling draft of air is produced artificially by suitable air forcing means, as a driving or suction fan, or fans, within an enclosure enclosing the supporting 40 surface, which may be in the form of a rink enclosing a surface of large area or a tunnel like structure enclosing a long and narrow supporting surface, as preferred.

My invention may also be made to serve an educational purpose in teaching unskilled operators the use of propelling sails, and where the supporting surface is water and the propelled vehicles are sail boats, in teaching the rudiments of small boat handling.

50 In the accompanying drawing,

Fig. 1 represents a plan view of one embodiment of my invention in which the supporting surface is a pool of water, the roof of the enclosing structure being removed.

55 Fig. 2 is a vertical section of the arrange-

ment illustrated in Fig. 1, showing the roof of the enclosing structure.

Fig. 3 is a view similar to Fig. 2, in which a supporting surface of ice is illustrated.

Fig. 4 is a view similar to Fig. 2, in which 60 the supporting surface is shown as a floor or pavement.

Fig. 5 is a horizontal section partly broken away of a construction in which the vehicles are propelled through long narrow tunnel 65 like passages.

In Figs. 1 and 2, I have shown an embodiment of my invention in which a supporting surface of water, indicated at 1, and contained in a suitable pool, or receptacle, 2, conveniently provided at one or more sides with a platform, 3, to afford room for spectators, and a landing place for the boats is enclosed in a suitable building, the walls of which are indicated at 4, and the roof at 5. An artificial 70 wind or draft of air is caused to travel over the supporting surface in one or more directions. In this instance, I have shown fans, 6 and 6^a, arranged at opposite ends of the building out of alignment with each other, 75 and provided with wide nozzles, 7 and 8, respectively, for discharging blasts of air over the surface of the water and longitudinally of the building, on opposite sides of its longitudinal center and in opposite directions 80 respectively, although I do not wish to be limited to this particular arrangement. I have also shown each of the fans provided with a flaring intake, indicated at 9 and 10, respectively, connected by suitable pipes, 11 and 12, with the fan casings, the intake for 85 each fan being located in alignment with the discharge nozzle of the fan at the opposite end of the building. This arrangement provides an interior circulation entirely within 90 the building and independent of the exterior atmosphere. The fans may be operated by suitable means, and I have indicated in Fig. 1,

motors at 13 and 14, for this purpose. In this instance, I have shown a plurality of 100 small sail boats indicated at 15, each of which is provided with a main sail, 16, jib, 16^a, rudder, 17, and tiller, 18. The arrangement of sails may be of any desired character, either 105 square or fore-and-aft, and in the present instance I have shown each of the boats provided with fore-and-aft sails, which will enable it to be operated under the direction of the operator carried thereby either with, against, or across the wind, provided by either of the 110

fans, 5 and 6. The boats are entirely uncircumscribed in their movements over the supporting surface, except by the limitations of the pool, and can be maneuvered at the will of the operator and made to travel in any desired direction by properly trimming the sails and operating the rudders. This embodiment of the invention not only provides amusement, but also provides for the education of children and inexperienced persons in the rudiments of small boat handling, enabling them to acquire a knowledge of setting and trimming a sail, steering a wind propelled boat, making landings, etc.

In Fig. 3, I have illustrated a modification of the invention in which the corresponding parts are given the same reference numerals, with the addition of 100. In this instance, the surface is ice, indicated at 101, which may be artificially frozen by means of suitable refrigerating pipes, indicated at 120, with which the pool, 102, may be provided. In this instance, vehicles suitable to the supporting surface will be provided, and I have shown, for example, ice boats, indicated at 115, provided with supporting runners, indicated at 115^a, one of which is provided with a tiller, 118, for steering the boat, which is provided with the usual main sail, 116, and jib, 116^a. I have also illustrated a skater at 121, provided with suitable ice skates, indicated at 122, and carrying propelling sails, 123, in this instance secured to a cross bar, which is held in the hands of the skater in the usual manner, the direction of movement of the skater being determined according to his own inclination by properly guiding the skates and manipulating the sails, 123. It will be understood that the supporting surface may be provided with ice boats only, or may be used entirely by skaters operating by the aid of sails under the action of the artificial draft of air, or the surface may be used for both purposes, as preferred.

In Fig. 4, I have illustrated another modification of my invention, in which the corresponding parts to those in Figs. 1 and 2 are given the same reference numerals with the addition of 200. In this instance, the supporting surface is a floor, or pavement, indicated at 201, in an enclosing building, provided with a fan, 206^a, or fans, for creating a draft of air over the supporting surface in the same manner as hereinbefore described with reference to Figs. 1 and 2. In this instance, the supporting surface may be provided with wheeled vehicles, as at 215, provided with sails, as at 216 and 216^a, for example, and having a suitable steering wheel, indicated at 218, for guiding the vehicles over the surface in any desired direction under the influence of the artificial draft of air. The surface may also be used by skaters, 221, provided with roller skates, 222, and the usual

skate propelling sails, indicated at 223, and carried by the skaters in the same manner as in the case of ice skates, or in any other desired way. The arrangement shown in Fig. 4 may be used for skaters alone, or for wheeled vehicles, or both, as may be preferred.

In Fig. 5, I have shown another embodiment of my invention in which the corresponding parts to those shown in Figs. 1 and 2 are given the same reference numerals with the addition of 300. In this figure the supporting surface is enclosed by a tunnel like structure, or structures, and swept longitudinally by an artificial draft of air in one direction only, so that the movement of the vehicles and their passengers will proceed in substantially the same general direction, while permitting them to be guided within the limitations of the lateral width of the tunnel, which will be sufficiently greater than that of any vehicle, to permit a certain freedom and independence of movement of the vehicle. In the form illustrated in Fig. 5, I have shown a pair of tunnels arranged side by side and communicating at their ends, as this forms a convenient arrangement and enables the vehicles to proceed in one direction through one tunnel and return to the starting point through the other. As shown in Fig. 5, the enclosing building comprises the side walls, 304, and a central partition, 304^a, with an appropriate roof structure, not shown, the side walls and partition being shown in section. The partition is shown as of less length than the building, and the side walls are conveniently connected by curved end walls, 304^b, thus forming two tunnel like passages communicating at their extremities with each other, by the apertures, 304^c, between the ends of the partition and the adjacent end walls. In this instance, I have shown the building provided with a supporting surface of water indicated at 302, 302, and vehicles in the form of boats, 315, provided in this instance with square sails, 316, and with rudders, 317, and tillers, 318. I have shown the building provided with air forcing fans, as 306 and 306^a, located at opposite ends of the building and each discharging an artificial draft of air longitudinally of one of the tunnel sections. The air from one tunnel may be permitted to pass into the other tunnel through the aperture, 304^c, remote from the fan, if desired, suitable means being provided for the escape of surplus air, as by ventilators in the roof, or I may provide a flaring intake, 309, at the end of each tunnel remote from the fan and communicating with the fan for the other tunnel, as shown in Fig. 5. A suitable landing platform indicated at 303, may be provided at one or both ends of the building. In the present instance, I have shown it provided with such a landing platform at one

end only. It will be obvious that the arrangement shown in Fig. 5 can be employed with a supporting surface of ice, or with a floor or pavement, and that suitable vehicles provided with runners or wheels, or rollers, may be employed in connection with such surface, and they may also be used with appropriate skates and sails carried by the skaters. In this form of my invention, the 10 artificial draft of air will be forced longitudinally of the tunnel, carrying the vehicles before it, the occupants of the vehicles, or the skaters, as the case may be, directing their movements within the limitation of the 15 width of the tunnel, and in the embodiment of my invention shown in Fig. 5, passing from one tunnel to the other at the ends thereof around the respective ends of the partition, 304^a.

20 It will be seen that in all the embodiments of the invention the vehicles, within which term I include skates used by skaters carrying propelling sails, are moved over the enclosed supporting surface by an artificial draft of air under the guidance of the operators carried thereby, without being circumscribed by any common guiding or propelling means, the 25 said vehicles being wholly unconnected with respect to each other. In all forms of the invention, in addition to the amusement and recreation provided, there will be an educational effect in the use of handling or propelling sails, and in the case of a water surface provided with sailing boats, unskilled and immature operators will readily acquire the rudiments of small boat handling under conditions which are free from the dangers attending the 30 use of small boats by inexperienced persons upon open water.

40 I also wish it to be understood that the embodiments of my invention are illustrated herein in a more or less diagrammatic manner, and that variations may be made in the construction and arrangement of the means for carrying my invention into effect without departing from the spirit of the invention.

45 While I have shown my invention embodied in connection with supporting surfaces enclosed within a building, I desire it to be understood that it is also applicable to the propulsion of passenger carrying sail propelled vehicles such as described herein, upon unenclosed supporting surfaces, as for example a small pond in the open, although obviously the 50 power required to operate the air forcing devices in connection with my invention could be more economically applied within a confined space or enclosure.

55 What I claim and desire to secure by Letters Patent is:—

60 1. Apparatus for amusement and recreation comprising an enclosed supporting surface for supporting passenger carrying vehicles provided with sails and guiding devices operable by passengers carried thereby, and

means for producing an artificial draft of air over said surface for the purpose of propelling said vehicles.

2. Apparatus for amusement and recreation comprising an enclosed supporting surface, 70 means for producing an artificial draft of air over said surface, and passenger carrying vehicles provided with sails movable over said surface independently of each other under the guidance of operators carried thereby. 75

3. Apparatus for amusement and recreation comprising an enclosed supporting surface, means for producing an artificial draft of air over said surface, and passenger carrying vehicles provided with sails and steering means, 80 the sails and steering means of each vehicle being capable of being operated by an operator carried thereby, to determine the direction of movement imparted to each of said vehicles by the draft of air, said vehicles being 85 unconnected and movable independently of each other.

4. Apparatus for amusement and recreation comprising an enclosing building, a horizontal supporting surface within the same, a 90 plurality of air forcing devices for producing artificial drafts of air in different directions over said supporting surface, and independently movable sail propelled vehicles movable over said surface and capable of being 95 steered by an operator carried thereby.

5. Apparatus for amusement and recreation comprising an enclosing building, a horizontal supporting surface within the same, an air forcing device located at one end of the building and discharging an artificial draft of air over a portion of said surface, an air forcing device located at the opposite end of the building for producing an artificial draft of air over another portion of the said surface in the 100 opposite direction, and independent sail propelled vehicles movable independently over said surface and capable of being steered by operators carried thereby. 105

6. Apparatus for amusement and recreation comprising an enclosing building, a horizontal supporting surface within the same, an air forcing device located at one end of the building and discharging an artificial draft of air over a portion of said surface, an air forcing device located at the opposite end of the building for producing an artificial draft of air over another portion of the said surface in the opposite direction, and independent sail propelled vehicles movable 110 independently over said surface and capable of being steered by operators carried thereby, each of said air forcing devices being provided with an intake in substantial alignment with the air forcing device at the opposite 115 end of said supporting surface. 120

7. Apparatus for amusement and recreation comprising an enclosing building, provided with a longitudinal partition dividing it into parallel passages communicating with each 130

- other adjacent to the ends of the building, and provided with a horizontal supporting surface, means for producing an artificial draft of air over said surface in opposite directions on opposite sides of said partition, and passenger carrying vehicles provided with propelling sails adapted to be moved longitudinally through said passages over said supporting surface by said draft of air.
10. 8. Apparatus for amusement and recreation comprising an enclosing building, provided with a longitudinal partition dividing it into parallel passages communicating with each other adjacent to the ends of the building, and provided with a horizontal supporting surface, means for producing an artificial draft of air over said surface in opposite directions on opposite sides of said partition, and passenger carrying vehicles provided with propelling sails adapted to be moved longitudinally through said passages over said supporting surface by said draft of air, said vehicles being unconnected with respect to each other and provided with independent steering means operable by an operator carried by the vehicle.
9. Apparatus for amusement and recreation comprising an enclosing building provided with a centrally located partition dividing it into separated longitudinal passages communicating with each other adjacent to the ends of the building, air forcing devices at opposite ends of the building for producing a draft of air longitudinally through each of said passages in a direction opposite to that of the draft of air in the adjacent passage, a horizontal supporting surface within each of said passages, and independently movable passenger carrying vehicles provided with propelling sails and

steering mechanism operable by passengers carried by the vehicles, movable over said supporting surface through said passages under the influence of the draft of air passing therethrough.

10. Apparatus for amusement and recreation comprising an enclosing building provided with a centrally located partition dividing it into separated longitudinal passages communicating with each other adjacent to the ends of the building, air forcing devices at opposite ends of the building for producing a draft of air longitudinally through each of said passages in a direction opposite to that of the draft of air in the adjacent passage, a horizontal supporting surface within each of said passages, and independently movable passenger carrying vehicles provided with propelling sails and steering mechanism operable by passengers carried by the vehicles, movable over said supporting surface through said passages under the influence of the draft of air passing therethrough, and means for creating the air draft at the end of each passage remote from the air forcing device therefor, and delivering it to the air forcing device for the adjacent passage.

11. Apparatus for amusement and recreation comprising unconnected passenger carrying vehicles provided with sails and guiding devices operable by passengers carried thereby, for propelling them and guiding them upon a supporting surface, and means for producing an artificial draft of air over the supporting surface for the purpose of propelling said vehicles.

In testimony whereof I affix my signature.

HAROLD T. PULSIFER.
